203,929

SANITARY CAT BOX

Henry E. Lowe, Jr., Cassopolis, Mich.

Filed June 28, 1965, Ser. No. 85,903

Term of patent 14 years

(Cl. D12—2)

FIG. 1

FIG. 6

FIG. 3

FIG. 2

Des. 203,929

PAGE 5

FIG. 5

FIG. 4

FIG. 7

FIGURE 1 is a perspective view of a sanitary cat box embodying the present invention;

I claim:

The ornamental design for a sanitary cat box, substantially as shown.
